WILLIAM E. STEWART, OF SOUTH GLENS FALLS, NEW YORK, ASSIGNOR OF ONE-HALF
TO THEODORE STOUGHTON, OF SOUTH GLENS FALLS, NEW YORK.

SELF-CLEARING SILENCER FOR PAPER-MAKING MACHINES.

Application filed November 18, 1920. Serial No. 424,808.

To all whom it may concern:

Be it known that I, WILLIAM E. STEWART, a citizen of the United States, and a resident of South Glens Falls, in the county of Saratoga and State of New York, have invented certain new and useful Improvements in Self-Clearing Silencers for Paper-Making Machines, of which the following is a full, clear, and exact description.

10 Among the principal objects which the present invention has in view are: To prevent the formation of masses of pulp in the stock as the same is delivered from the header box to the wire belt on which the

15 said stock is spread in the initial step of the sheet forming process; to secure an even speed of the stock to the said belt to prevent clogging of the stock or thickening of the same adjacent the delivery of the stock from

20 the said box; and to simplify and cheapen the construction and installation of the said silencer.

Drawings.

25 Figure 1 is a top plan view of a header box having installed therein, a silencer constructed and arranged in accordance with the present invention.

30 Figure 2 is a side view of the same, the flight arrows being employed therein as showing the direction of the flow of the pulp bearing stock through header box and silencer.

Description.

35 Heretofore, header boxes have been provided with some form of perforated or slotted partition disposed across the said box adjacent the delivery end thereof. This partition has been called a silencer box.

40 The principal function thereof has been to quiet the up-flow of the stock passing to the tail board or delivery member of the said box wherefrom the stock is floated onto the sheet-forming belt of the paper making machine. These partitions or silencers have

45 been subject to the difficulty that the pulp contained in the stock has tended to mat on the silencer to form small masses of partly attached pulp, which after a time have

50 been carried through the silencer by the stream of stock rising through the same, and have passed in this matted condition onto the belt, and in the process of forming a sheet, marred or imperfect sections have been

55 produced by the said matted masses. Means

have been devised for preventing the clogging of the stock against the under-surface of the silencer. These means, however, have been inefficient and faulty dependent, as they have done, on breaking up or scattering the 60 masses referred to. The fault has arisen largely from the fact that preventive means has operated after, instead of prior to the formation of the matted masses, hence, it often occurs that the mass is either driven 65 through the interstices of the silencer in part, or wholly form, thus defeating the purpose for which the clearing device was employed.

In the present invention a cylinder 8 is 70 fixedly mounted on a shaft 9 which rotates in varying boxes 10 set in the sides of the header box 11. The cylinder 8 is preferably disposed so that the outer surface of the cylinder 8 passes sufficiently close to the 75 edge of the tail board to prevent any masses of pulp passing therebetween. In this position the opposite side of the cylinder 8 is depressed in close adjacency to the baffle plate 13 which extends downward into the 80 box 11 to form the last vertical passage in the said box.

The cylinder 8 is preferably made up of a number of short length cylinders, as at 8', which, as seen best in Figure 1 of the drawings, are disposed in service, end to end. By this arrangement the length of the cylinder 8 may be varied to suit various widths of header boxes.

The shaft 9 is provided with a pulley 14 90 which, as seen best in Figure 2 of the drawings, is operatively connected by the belt 15, with a small pulley 16 on the drum 17, over which the meshed wire belt 18 is driven. This arrangement provides for slowly rotating the cylinder 8. The cylinder 8 is provided with perforations 19 which are spaced apart to adapt the silencer to the work for which it is designed. The stock freely passes through the perforations 19 to the interior of the cylinder 8 and therefrom on the opposite side of the said cylinder. It will be seen that if the pulp is arrested and matted on the surface of the cylinder at the time when the stock is flowing into the said 100 cylinder, the matted pulp is cleared from the cylinder as the stock flows from out thereof at the delivery side of the said cylinder. Due to the slow but constant revolution of the cylinder the stock is prevented 110

from matting or massing to any considerable extent for the reason that the time therefor is not permitted in the operation of the cylinder, the receiving face passing constantly away from the receiving side of the said cylinder to the delivery side thereof. While in the accompanying drawings the cylinder 8 is shown as being constructed from sheet metal perforated, it will be understood that other forms of metal such as expanded metal, or wire cloth of suitable construction may be employed. This variation in the construction is considered as coming within the scope of the present claims.

15

Claims.

1. In combination with a header box having a delivery opening and a baffle plate adjacent thereto for forming a vertical narrow channel leading to said delivery opening; a perforated cylinder rotatively mounted

20

in said channel, said cylinder extending fully across said channel.

2. In combination with a header box having a delivery opening and a baffle plate adjacent thereto for forming a vertical channel leading to said delivery opening, and a silencer disposed crossways of said channel and in close proximity to said delivery opening and in the path of the stock flowing therethrough.

3. In combination with a header box having a delivery opening and a baffle plate adjacent thereto for forming a vertical channel leading to said delivery opening, and a rotating cylinder adapted for the passage of stock therethrough, said cylinder being disposed crossways of said channel and in close proximity to said delivery opening and in the path of the stock flowing through said channel and opening.
